[57] CLAIM

The ornamental design for a child's protective shield for attachment between the backrests of automotive front seats, as shown.

DESCRIPTION

FIG. 1 is a front elevational view of a child's protective shield for attachment between the backrests of automotive front seats showing my design;

FIG. 2 is a rear view;

FIG. 3 is a top plan view; and

FIG. 4 is a side elevational view thereof.

FIG. 3
